UNITED STATES PATENT OFFICE.

FRANK B. YINGLING, OF HAMILTON, OHIO.

SHAPER-FEED.

1,315,449.

Specification of Letters Patent.

Patented Sept. 9, 1919.

Application filed November 15, 1918. Serial No. 262,706.

To all whom it may concern:

Be it known that I, FRANK B. YINGLING, a citizen of the United States, residing at Hamilton, Butler county, Ohio, have invented certain new and useful Improvements in Shaper-Feeds, of which the following is a specification.

This invention pertains to improvements in the feed mechanism for metal shapers, and the improvements will be readily understood from the following description taken in connection with the accompanying drawings in which:

Figure 1 is a side elevation of a portion of the body of a shaping machine provided with an exemplification of my improvement in feed mechanism, a part in this view appearing in vertical section in the plane of line *d* of Figs. 2 and 4:

Fig. 2 a plan of the same parts, the column appearing in horizontal section in the plane of line *f* of Fig. 1:

Fig. 3 a horizontal section in the plane of line *a* of Figs. 1, 4, 5 and 6:

Fig. 4 a vertical section in the plane of line *b* of Figs. 1, 2 and 3:

Fig. 5 a vertical section in the plane of line *c* of Figs. 1, 2 and 3: and

Fig. 6 a vertical section in the plane of line *c* of Figs. 2 and 3.

In the drawings:

1, indicates the column of an ordinary shaping machine:

2, its vertical front guideway:

3, the rail, arranged as usual to be adjusted vertically on this guideway:

4, one of the journals of the actuating mechanism of the shaper, this journal projecting out through one of the side-walls of the body: and

5, a bearing for this journal, having a concentric exterior projecting out from the body of the shaper.

It is the purpose of my improvements to cause the journal 4 to produce the feeding motion for the feed-screw of the rail, in such manner as to provide a satisfactory and convenient ratchet-feed which can be readily adjusted in degree, and direction of feeding motion, while the machine is in motion.

Proceeding with the drawings:

6, indicates a short countershaft journaled in one end of the rail, parallel with the rail, rearward of the face of the rail:

7, a pair of bevel-gears provided with separated clutch-hubs, mounted loosely on this countershaft, in a recess in the rear face of the rail, across which recess the countershaft passes:

7^a, a clutch-hub splined on the countershaft and adapted to lock a selected one of the two bevel-gears to the countershaft:

7^b, a pivoted hand-lever for throwing the clutch-hub, this hand-lever being provided with a spring detent to hold it either in the neutral position or with one of the bevel-gears clutched to the countershaft:

8, a splined shaft designed to have rotary motion imparted to it from the journal 4 and, in turn, to transmit intermittent motion to a selected one of the bevel-gears on the countershaft:

9, a bevel-gear loose on the forward end of this splined shaft and engaging the two bevel-gears 7:

10, a casing swiveled on the bearing 5 and split vertically to permit its attachment to the bearing 5:

11, a bearing projecting forwardly from this casing and forming a bearing for the shaft 8, the axis of which shaft is some distance below the axis of bearing 4, bearing 11 having a cylindrical exterior concentric with shaft 8:

11^a, an eccentric secured to the outer end of journal 4, outwardly beyond shaft 8:

11^b, an eccentric-rod having strapped engagement with the eccentric:

12, a forked arm formed in two halves, 90 splined on shaft 8, this arm having concentric hubs journaled in the casing 10:

13, a crosshead fitted to slide vertically in casing 10 below and outwardly beyond the eccentric:

14, a horizontal crosshead pin projecting from the cross head toward the body of the shaper: and

15, a block, fitted to turn and slide on this pin, this block being disposed within the bifurcation of forked arm 12 and having trunnions engaging the bifurcations.

As the journal 4 revolves it causes the eccentric to reciprocate pin 14, which reciprocation produces an oscillating motion for 105 splined shaft 8. The crosshead guides the lower end of the eccentric-rod vertically, and the sliding of block 15 on the pin compensates for the arc of movement of the trunnions of the block. The split case 10 110

permits it to be readily applied to the bearing 5, and the splitting of forked arm 12 permits trunnion block 15 to be readily put in place.

5 Proceeding with the drawings:—

16, indicates a horizontally split case for the bevel gears on the countershaft, the case being swiveled relative to the countershaft:

17, a concentric hub projecting rearwardly from this case and loosely fitting the rearwardly projecting hub of bevel-gear 9:

18, a horizontally split ratchet-case swiveled upon hub 17:

19, a rearward prolongation of case 18 swiveled upon bearing 11 and having a sliding engagement with bearing 11:

20, a toothed segment fixed to hub 17, within case 18:

21, a handle projecting outwardly from case 18 to facilitate the angular adjustment of case 18 relative to case 16: and

22, a spring detent-pin carried by case 18 and engaging a selected tooth in segment 20.

Casings 10, 16 and 18, together, form a casing swiveled at one end upon the countershaft and upon the other end to bearing 5, parts 11 and 19 constituting a telescopic arrangement which permits the general length of the casing to alter itself as the rail 30 is adjusted higher or lower upon the column of the machine. It is in this general casing that splined shaft 8 is journaled, its spline permitting it to slide through forked arm 12 as the length of the general casing becomes altered. Ratchet case 18 may be adjusted angularly with reference to the two other casing members, by means of handle 21, the detent pin 22 serving to fix the ratchet-case in adjusted position. The spring 40 of detent pin 22 is illustrated as being disposed within the handle 21. The juncture between cases 16 and 18 may be graduated to indicate the angular position into which case 18 has been adjusted by means of handle 21.

Proceeding with the drawings:—

23, indicates a ratchet-wheel fast on the hub of bevel-gear 9, within the ratchet-casing, so that the turning of the ratchet-wheel 50 will effect the turning of bevel-gear 9:

24, a pawl-carrier keyed to the splined shaft alongside the ratchet-wheel:

25, a spring-pawl carried by the pawl-carrier and engaging the ratchet-teeth:

55 26, a roller carried by pawl 25:

27, a trackway on the inwall of the ratchet case, adapted to be engaged by roller 26 and cause the pawl to be held out of engagement with the ratchet-teeth so long as the roller is 60 traversing the trackway:

28, a spring stop-pawl carried by segment 20 and adapted to engage a tooth in the ratchet-wheel and prevent pawl 25 from dragging the ratchet-wheel backward on the 65 return stroke of pawl 25:

29, a gear loose on the outer projecting end of counter-shaft 6:

30, friction-disks serving to lock gear 29 yieldingly to the counter-shaft:

31, the feed-screw of the rail, the end of 70 this screw projecting, as usual, from the end of the rail to receive a crank by means of which the screw may be turned:

32, a pinion mounted on the projecting end 75 of the rail screw and engaging gear 29, this pinion being preferably removable from the end of the rail-screw: and

33, the usual horizontal shaft journaled in the rail, to be bevel-geared to the elevating screw of the rail, this shaft projecting from 80 the end of the rail and being adapted to be turned by hand, or, if desired, to have placed upon it the pinion 32 removed from the rail screw.

Looking at Fig. 5, and understanding that 85 the shaft 8 is given an oscillating motion by means of the mechanism driven by the eccentric, it is obvious that the pawl-carrier and pawl will bring about an intermittently advancing rotation of the ratchet-wheel and of bevel-gear 9. Normally, the degree of advance of the ratchet-wheel would be measured by the stroke of the pawl-carrier, and the intermittently advancing motion of bevel-gear 9 will be transmitted to the countershaft when the clutch is thrown by means of 90 the hand-lever 7^b.

This motion of the countershaft becomes 100 transmitted to the rail screw, and if the limit of feeding motion of the rail screw be exceeded then friction-disk 30 permits gear 29 to stand while the countershaft slips. It is my desire that the position of hand lever 7^b shall indicate the direction of feed, that is to say, when the hand-lever is adjusted to position away from the column of the shaper, the rail-screw will effect a corresponding feeding motion, while if the hand-lever be adjusted toward the shaper column the rail screw will effect a feeding motion in the 105 opposite direction, or the hand-lever may be locked by its detent in the neutral position.

Looking again at Fig. 5, and giving consideration to the trackway 27, as the parts are shown the pawl-carrier may effect the 110 advance of the ratchet-wheel throughout its forward stroke, which the drawing shows as having been just completed. The trackway is in such case without office. But if case 18 be angularly adjusted so that detent 115 pin 22 is in the final instead of the initial notch in segment 20, then trackway 27 comes into play and is engaged by roller 26 throughout the forward and backward strokes of the pawl carrier, and the pawl will be at all times free from the ratchet wheel. If, now, casing 18 be angularly adjusted so that the detent pin engages some intermediate notch in segment 20, then roller 26 will engage the trackway for during 120 125 130

a portion of its stroke only, and the pawl will engage the ratchet wheel and advance it during only the remainder of the stroke of the pawl. By this means the degree of 5 advance of the feed may be regulated without stopping the shaper, and so, also, may hand-lever ^{7b} be thrown to either of its extremes or the neutral without stopping the machine.

10 It is to be understood that the mechanism particularly set forth embodies but a single exemplification of my invention. I have sought to explain the principle of my invention and the best mode in which I at 15 present contemplate embodying that principle.

I claim:

1. Shaper-feed mechanism comprising, a rail, a rail-screw, a shaft projecting sidewise from the body of the shaper, a telescopic bearing-structure articulated to the rail and to said projecting shaft, a splined-shaft mounted in said bearing, mechanism connecting the projecting shaft with the 20 splined-shaft and serving to give to the splined-shaft an oscillating motion on its axis, and mechanism connecting the splined-shaft with the rail-screw and adapted to intermittently advance the rail-screw, combined substantially as set forth.

2. Shaper-feed mechanism comprising, a rail, a rail-screw, a shaft projecting sidewise from the body of the shaper, a telescopic bearing-structure articulated to the rail and 25 to said projecting shaft, a splined-shaft mounted in said bearing, mechanism connecting the projecting shaft with the splined-shaft and serving to give to the splined-shaft an oscillating motion on its axis, and reverse mechanism connecting the 30 splined-shaft with the rail-screw and adapted to intermittently advance the rail-screw in either direction, combined substantially as set forth.

45 3. Shaper-feed mechanism comprising, a rail, a rail-screw, a counter-shaft journaled in the rail, gearing connecting the counter-shaft with the rail-screw, a shaft projecting sidewise from the body of the shaper, a 50 telescopic bearing-structure articulated to the rail and to said projecting shaft, a splined-shaft mounted in said bearing, mechanism connecting the projecting shaft with the splined-shaft and serving to give to the 55 splined-shaft an oscillating motion on its axis, and mechanism connecting the splined-shaft with the counter-shaft and adapted to intermittently advance the rail-screw, combined substantially as set forth.

60 4. Shaper-feed mechanism comprising, a rail, a rail-screw, a shaft projecting sidewise from the body of the shaper, a telescopic bearing-structure articulated to the rail and to said projecting shaft, a splined- 65 shaft mounted on said bearing, mechanism

connecting the projecting shaft with the splined-shaft and serving to give to the splined-shaft an oscillating motion on its axis, mechanism connecting the splined shaft with the rail-screw and adapted to intermittently advance the rail-screw, and a friction-device interposed in the last-mentioned mechanism and adapted to permit the splined-shaft to slip relative to the rail-screw, combined substantially as set forth. 75

5. Shaper-feed mechanism comprising, a rail, a rail-screw, a counter-shaft journaled in the rail, gearing connecting the counter-shaft with the rail-screw, a shaft projecting sidewise from the body of the shaper, a 80 telescopic bearing-structure articulated to the rail and to said projecting shaft, a splined-shaft mounted in said bearing, mechanism connecting the projecting shaft with the splined-shaft and serving to give to the splined-shaft an oscillating motion on its axis, mechanism connecting the splined-shaft with the counter-shaft and adapted to intermittently advance the rail-screw, and a friction device interposed between the 85 splined-shaft and the counter-shaft to permit the splined-shaft to slip relative to the counter-shaft, combined substantially as set forth.

6. Shaper-feed mechanism comprising, a rail, a rail-screw, a shaft projecting sidewise from the body of the shaper, a telescopic bearing-structure articulated to the rail and to said projecting shaft, a splined-shaft mounted in said bearing, bevel-gearing between the splined-shaft and the rail-screw, a ratchet-wheel connected with the bevel-gearing, a pawl-carrier fast on the splined-shaft, a pawl carried by the pawl-carrier and engaging the ratchet-wheel, and mechanism between said projecting shaft and said splined-shaft to serve in giving to the 100 splined-shaft a motion of oscillation on its axis, combined substantially as set forth. 105

7. Shaper-feed mechanism comprising, a rail, a rail-screw, a shaft projecting sidewise from the body of the shaper, a telescopic bearing-structure articulated to the rail and to said shaft, a splined-shaft mounted in said bearing, mechanism connecting the projecting shaft with the splined-shaft and serving to give to the splined-shaft an oscillating motion on its axis, a toothed segment concentric with said splined-shaft and fixed relative to it, a casing-part swiveled 110 with reference to the splined-shaft, a detent to lock said casing-part in adjusted relationship to said notched segment, a ratchet-wheel mounted on the splined-shaft and having geared connection with the rail-screw, a 115 pawl-carrier fast on the splined-shaft, a spring pawl carried by the pawl-carrier and engaging the ratchet-wheel, and a trackway carried by said casing and concentric with the ratchet-wheel and adapted to engage the 120 125 130

- pawl and hold it out of action with the ratchet-wheel, combined substantially as set forth.
8. Shaper-feed mechanism comprising, a rail, a rail-screw, a shaft projecting sidewise from the body of the shaper, a telescopic bearing-structure articulated to the rail and to said shaft, a splined-shaft mounted in said bearing, mechanism connecting the splined-shaft with the rail-screw, an eccentric on said projecting shaft, an arm splined on the splined-shaft, and an eccentric-rod connecting the eccentric and arm, combined substantially as set forth. 40
- 15 9. Shaper-feed mechanism comprising, a rail, a rail-screw, a shaft projecting sidewise from the body of the shaper, a telescopic bearing-structure articulated to the rail and to said shaft, a splined-shaft mounted in said bearing, mechanism connecting the splined-shaft with the rail-screw, an eccentric on said projecting shaft, an arm splined on the splined-shaft, a block trunnioned to said arm, a crosshead pin connected with the block, a crosshead on the crosshead pin, a guide for the crosshead, and an eccentric-rod connecting the eccentric and the crosshead pin, combined substantially as set forth. 45
- 20 10. Shaper-feed mechanism comprising, a shaft projecting sidewise from the body of the shaper, a diametrically divided casing swivelled to said shaft, a bearing carried by said casing tangent to a circle concentric with said projecting shaft, a splined-shaft 50
- 25
- 30
- 35
- sliding in said bearing, a divided forked arm having its hub mounted in said bearing and splined to said splined shaft, mechanism connecting said projecting shaft and forked arm and adapted to give the splined shaft a motion of oscillation upon its axis, and mechanism connecting the splined shaft with the rail-screw to serve in giving an intermittent advance to the rail-screw, combined substantially as set forth. 55
11. Shaper-feed mechanism comprising, a rail, a countershaft journaled in the rail of the shaper, a divided gear-case swiveled with reference to the countershaft and provided with a concentric hub, a shaft projecting sidewise from the body of the shaper, a casing swiveled with reference to said projecting shaft and provided with a bearing projecting toward the first-mentioned casing, a longitudinally divided intermediate casing-part connecting said bearing and the hub, means for angularly adjusting said intermediate casing-part, a splined-shaft journaled in the three casing-parts, mechanism disposed in the second named 60 casing for giving the splined shaft a motion of oscillation upon its axis, reversing gearing disposed in the first-mentioned casing, and pawl and ratchet mechanism disposed in the intermediate casing, combined substantially as set forth. 65
